UNITED STATES PATENT OFFICE.

ANDREW MANYAK AND MARY MANYAK, OF NANTY GLO, PENNSYLVANIA.

ADJUSTABLE SCREEN.

1,341,188.

Specification of Letters Patent. Patented May 25, 1920.

Application filed September 29, 1919. Serial No. 327,024.

To all whom it may concern:

Be it known that we, ANDREW MANYAK and MARY MANYAK, citizens of Poland, and residents of Nanty Glo, in the county of Cambria and State of Pennsylvania, have invented certain new and useful Improvements in Adjustable Screens, of which the following is a specification.

This invention relates to window screens and the like, particularly to such apparatus which are of changeable size, and has for its object to provide an adjustable window screen which may be adapted to window frames of different sizes and which is both simple in manner of construction and operation and inexpensive in cost of manufacture.

The above and other objects will become apparent in the description below, in which like characters of reference refer to like-named parts on the drawings.

Referring briefly to the drawings, Figure 1 is a front elevational view of our adjustable screen.

Fig. 2 is a plan view of the same.

Fig. 3 is a cross-sectional view taken substantially on the line 3—3 of Fig. 1.

Referring now in detail to the drawings, the numeral 1 represents the frame of one section of our adjustable screen, and the 30 numeral 2 the other frame thereof. The rear frame 2 is provided with overlapping projecting members 5 and 6, which grip the upper and lower frame members of the screen 1. Thus said member 5 overlaps and 35 grips member 8. It is thus apparent that the frame 1 readily slides in said overlapping members 5 and 6 so that the total length of the screen may be varied to suit the window in which it is placed. We have 40 illustrated a two-part adjustable screen, though it is apparent that, without departing from the spirit of our invention, three or more parts may be used in the same manner.

45 We provide releasable locking means comprising a wing or thumb screw 7 rotatably

mounted in the beak portions of the members 5 and 6, said screws having screw-thread engagement with said beaks. The bases of said screws, that is, the parts which engage the opposite frame, are broadened to provide disks 11, so that the tightening force upon the screw is spread over a greater area upon the frame 8, for instance, thus preventing crushing of the material comprising that frame. The stem of said screw is indicated by 12. If desired, to further prevent such damage, a layer of rubber or the like 9 may be provided over the surface 8.

After our screen has been extended, or retracted, to the desired length, the screws 7 are tightened so as to clamp the frames of the opposite screen member and thus retain the whole as one solid screen.

Having thus described our invention, what we claim and desire to secure by Letters Patent is as follows:

In a device of the class described a plurality of sections having frame members 70 containing screens, means for slidably retaining said members in adjustable position, said means consisting in having the upper and lower frame members of one of said sections extended and overlapping the corresponding frame members of an adjacent section, the latter adapted to slide in the former, and means for locking said sections in position comprising wing screws rotatable in the said frame members in said first-named section, said screws passing through said frame members and the stems thereof engaging said corresponding frame members, the ends of said stems being widened and having tips of rubber thereon, said tips 80 adapted to be clamped against said corresponding frame members.

Signed at Expedit, in the county of Cambria and State of Pennsylvania, this 22nd day of Sept., A. D. 1919.

ANDREW MANYAK.
MARY MANYAK.
